HENRY P. KRAFT, OF BROOKLYN, NEW YORK, AND MAXIMILIAN CHARLES SCHWEINERT, OF WEST HOBOKEN, NEW JERSEY.

VALVE.

1,377,590.

Specification of Letters Patent. Patented May 10, 1921.

Application filed February 17, 1909. Serial No. 478,845.

To all whom it may concern:

Be it known that we, HENRY P. KRAFT, residing in the borough of Brooklyn, county of Kings, city and State of New York, and MAXIMILIAN CHARLES SCHWEINERT, residing in West Hoboken, in the county of Hudson and State of New Jersey, both citizens of the United States, have jointly invented certain new and useful Improvements in Valves, of which the following is a specification.

This invention aims to provide certain improvements especially applicable to pressure indicating valves for pneumatic tires, and applicable also in whole or in part to valves for various other purposes.

The accompanying drawings illustrate an embodiment of the invention.

Figures 1, 2, 3 and 4 are diametral sections of different types of valve embodying the invention;

Fig. 5 is a cross-section on the line 5—5 of Fig. 1. Except as indicated in Fig. 5 the parts are generally of circular cross-section.

Referring to the embodiments of the invention illustrated, the valve shell A carries the usual parts of an ordinary or suitable tire valve such as the valve proper, seat, spring, stems, &c., of the common Schrader valve illustrated in Fig. 1, which are surrounded by an outer tube B which is threaded on the outside to receive a dust-cap covering the entire valve shell, and which is provided with flat outer faces to prevent its turning in the rim of the wheel, these features being common.

The outer tube directly surrounds the upper part of the valve shell A with a good sliding fit, so that the latter may slide out of the end of the outer tube B sufficiently to indicate the pressure within the tire; the valve shell A being yieldingly held down in the outer tube by means of one or more helicoidal springs C and D, and by means of an elastic tube E through which an air-tight communicating passage is provided from the valve shell to the interior of the tire.

The arrangement and the details of these yielding connections are important in the making of a simple, easily assembled, and durable device.

Referring first to the construction of Fig.

1, the valve shell A is provided with a nipple F of reduced cross-section permitting the use of a straight outer tube B, and yet leaving a sufficient annular space for the attaching devices hereinafter referred to. The outer end of the elastic tube E is fastened on the nipple F, preferably by corrugating the latter and stretching the tube over the same (and wrapping the tube if necessary). The springs C and D are attached to the valve shell by means independent of the connection between the shell and the elastic tube, as for example by the screw threads of Figs. 2 and 3 or by an attaching ring G (Fig. 1) which is screwed at its upper end to a portion H of the valve shell which is of intermediate cross-section between that of the nipple F and the upper part of the shell. The spring C is attached to the attaching ring G by screwing the spring on the outside thereof, the reduction of cross-section from the portion H of the valve shell to the nipple F permitting a corresponding reduction of the lower part of the attaching ring G, so as to make room for the spring C between the attaching ring and the outer tube B. Thus the connection from the outer spring to the shell through the ring G extends above the connection of the elastic tube. The inner spring D has its convolutions arranged close together so as to prevent or materially limit diametral expansion of the elastic tube E, and is fastened upon the attaching ring G by screwing it within the lower end of the attaching ring, where the attaching ring extends below the valve shell, so that there is plenty of room. The attaching member G is suitably grooved or threaded to permit the screwing of the springs thereon. The attaching ring G is shouldered on the inside to correspond with the reduction in cross-section between the parts H and F of the valve shell, and the elastic tube E preferably extends upward sufficiently to have its ends pinched off flat between the shoulders of the attaching ring G and the part H.

The construction may be somewhat simplified by omitting the spring D and using a single spring C as in Figs. 2 and 3, and in this case the spring may be attached to the intermediate portion H of the valve shell directly by screwing it upon suitable threads.

thereon. The nipple F is attached to the end of the elastic tube E by merely extending the tube over the corrugated outer surface of the nipple and wrapping it thereon with 5 wire thread or the like.

The manner of attachment of the lower ends of the elastic tube and the springs is important in order to obtain simplicity and cheapness, and at the same time preserve an 10 air-tight connection. For this purpose preferably the constructions in Figs. 1, 2 and 3 are employed, in which the inner end of the tube is provided with an outward flange which is clamped between two suitable 15 members.

In the construction shown in Fig. 1 the springs C and D have their inner ends fastened to thimbles J and K respectively by means of screwthreads, as at the upper ends, 20 and these thimbles are provided with flanges L and M, which take under a shoulder upon a fixed member such as the head N on the inner end of the outer tube B. The flange O at the inner end of the elastic tube E is 25 clamped between said fixed member together with the flanges L and M by means of a nut P screwing into a threaded socket in the member N.

In the construction of Fig. 2 the shoulder 30 Q which supports the thimble J carrying the spring, is provided in the portion of the outer tube B beyond the head N, and the flange O of the elastic tube alone is clamped between said member N and the nut P.

In the construction of Fig. 3 the shoulder Q and thimble J' carrying the spring, is the same as in Fig. 2. The flange O' which is provided for the lower end with the elastic tube E, is a metallic flange on a thimble R having 40 a corrugated exterior upon which the tube is forced and wrapped the same as at its upper end. With this construction, in order to insure an air-tight joint, it is advisable to introduce a packing ring S of rubber, 45 leather, or other packing material between the flange O' and the nut P.

Any one of the connections illustrated for the upper ends of the elastic tube and springs may be used, either with or without 50 the particular style of connections previously described for the inner ends. For example instead of providing a flange at the inner end of the elastic tube which is clamped in place to hold it fast, the construction shown in Fig. 4 may be used, in which the tube has a hollow annular head T extending entirely around the head N of the outer tube B, and held in place by the inwardly extending edge of said head T 60 which incloses the head N. Various other modes of attachment of the inner end of the elastic tube may be adopted.

In previous apparatus of this general type it has been proposed to use the usual 65 dust-cap, or a similar cap screwing down

upon the outer tube B and pressing down upon the top of the valve cap U (Fig. 1) to prevent yielding of the springs and stretching of the inner tube except when the tire is first pumped up, so as to save strain on said 70 springs and tube. It is inadvisable however to press as hard upon the top of the cap as would sometimes be the case with this arrangement, and we propose to use a restraining device which shall avoid any strain on 75 the cap by acting upon the valve shell A. For this purpose a ring V is provided having a thread by which it may be introduced over the end of the valve shell, and seating upon a shoulder W on said shell, its 80 lower end being threaded to enter a threaded socket X in the tire of the outer tube B. By simply unscrewing the restraining ring V, the apparatus is free to yield to indicate the internal pressure, or by pressing down 85 and screwing in the ring V the parts are held in their normal unstrained position.

In order to prevent the valve shell A from rotating in the outer tube B, a slight projection Y (Fig. 5) is preferably formed 90 in the outer tube entering a longitudinal groove Z in the valve shell.

What we claim is:—

1. In a pressure indicating tire valve, the combination of a tube, a valve shell adapted 95 to have movement longitudinally in said tube, having an extension at its lower end of two reduced diameters, the lower portion of the extension being of less diameter than the portion above it, an elastic tube connected to one reduced portion of said shell and to said tube, and a coiled spring connection between the other reduced portion of said shell and said tube, whereby said elastic tube may be connected to said shell independently of said coiled spring connection. 100

2. In a pressure indicating tire valve, the combination of a tube, a valve shell adapted to have movement longitudinally in said tube, having an extension at its lower end 110 of two reduced diameters, the lower portion of the extension being of less diameter than the portion above it, an elastic tube connected to the more reduced portion of said shell and to said tube, and a coiled spring 115 connection between the less reduced portion of said shell and said tube, surrounding said elastic tube, whereby said elastic tube may be connected to said shell independently of said coiled spring connection. 120

3. In a pressure indicating tire valve, the combination of a tube, a valve shell adapted to move longitudinally in said tube having a body portion of substantially the same external diameter as the internal diameter of 125 said tube, and an extension of less diameter than its body portion upon its lower end constituting a nipple, and an elastic tube and a coiled spring connection between said tube and the nipple of said shell. 130

4. In a pressure indicating tire valve, the combination of a tube, a valve shell adapted to have movement longitudinally in said tube having an extension at its lower 5 end of two reduced diameters, the lower portion of the extension being of less diameter than the portion above it, an elastic tube connected to the more reduced portion of said shell and to said tube, a sleeve connected to the less reduced portion of said shell, and a plurality of coiled springs connected to said sleeve and said tube, whereby said elastic tube and springs are connected to said shell independently of one another.
- 10 5. In a pressure indicating tire valve, the combination of a tube having an internal shoulder at its lower end, a valve shell adapted to have movement longitudinally in said tube, an elastic tube connected to 15 said valve shell and tube, and a nut on the interior of said tube clamping said tube between it and said shoulder in said tube.
- 15 6. In a pressure indicating tire valve, the combination of a tube having an internal shoulder at its lower end, a valve shell adapted to have movement longitudinally in said tube, an elastic tube provided with 20 an outward flange at its lower end connected to said valve shell and tube, and a nut on the interior of said tube clamping the flange
- of said tube between it and said shoulder in said tube.
7. In a pressure indicating tire valve, the combination of a tube, a valve shell resiliently connected to said tube, and adapted to have movement longitudinally in said tube, and a retaining ring swiveled upon said shell and adapted to be connected to said tube for retaining said shell against movement.
- 25 8. In combination, a valve shell having at its inner end a nipple of reduced cross-section and an elastic tube fastened at one end on said nipple and adapted to maintain communication between said shell and a pneumatic tire, and an outer tube surrounding the larger portion of said shell and adapted for connection to said tire, the attaching means comprising a ring connected to the shell above the end of the elastic tube and to the spring.
- 30 In witness whereof we have hereunto signed our names in the presence of two subscribing witnesses.
